UNITED STATES PATENT OFFICE.

WILLIAM F. DRAPER, OF HOPEDALE, MASSACHUSETTS, ASSIGNOR TO DRAPER COMPANY, OF HOPEDALE, MASSACHUSETTS, A CORPORATION OF MAINE.

FILLING-REPLENISHING LOOM.

SPECIFICATION forming part of Letters Patent No. 726,518, dated April 28, 1903.

Application filed January 16, 1903. Serial No. 139,341. (No model.)

To all whom it may concern:

Be it known that I, WILLIAM F. DRAPER, a citizen of the United States, and a resident of Hopedale, county of Worcester, State of Massachusetts, have invented an Improvement in Filling-Replenishing Looms, of which the following description, in connection with the accompanying drawings, is a specification, like characters on the drawings representing like parts.

In present loom structures the shuttle when boxed is usually under considerable pressure between the binder and the opposite box-plate or wall of the shuttle-box, making any longitudinal movement of the shuttle more or less difficult. This resistance to longitudinal movement is increased by the use of various forms of shuttle-checks which impart additional pressure to the binder, as well as by the use of leather or other friction-producing material on the face of the binder.

In automatic looms of the Northrop type, such as shown in United States Patent No. 529,940, the shuttle is provided with an inclined plate at the end provided with holding means for the filling carrier or bobbin, the object of which plate is to cause movement of the shuttle toward the mouth of the shuttle-box if it is so far in that the base of the filling-carrier strikes the incline at the time of filling transfer. At such time the filling-carrier is held from lengthwise movement by a ridge on the face of the transerrer which engages the endmost ring on the base of the filling-carrier. When the shuttle is held by the checking means acting through the binder so tightly that the filling-carrier in transit cannot move the shuttle by striking on the incline, the filling-carrier is deflected from the proper horizontal position, its tip being depressed, for it must move lengthwise if the shuttle does not, and in order to so move the base of the filling-carrier must slide under the ridge of the transerrer. This is almost certain to result in breaking the filling-thread, and it is also liable to cause the tip of the filling-carrier to catch in the slot in the lay in the bottom of the shuttle-box.

My present invention has for its object the

production of means for preventing such highly-objectionable occurrences, and to this end I have made provision for relieving the shuttle from binding pressure as transfer of filling is effected. By so doing the shuttle can be moved readily into proper receptive position by the filling-carrier being transferred thereto, and lateral positioning of the shuttle is also permitted to a slight degree, completely obviating the objections herein-before referred to.

The various novel features of my invention will be described hereinafter in the subjoined specification and particularly pointed out in following claims.

Figure 1 is a transverse sectional view of a portion of a loom provided with automatic filling-replenishing mechanism, taken at the inner end of the filling-feeder on the line 11, Fig. 2, with one embodiment of my present invention applied thereto. Fig. 2 is a top or plan view of the lay and shuttle-box at the replenishing side of the loom and showing a part of the means for relieving the shuttle of binding pressure at the time of filling replenishment, and Fig. 3 is a longitudinal sectional view of a portion of the bunter-carrying lever shown in Figs. 1 and 2.

Referring to Fig. 1, the breast-beam A⁴⁰, the stand A⁷, mounted thereon near one side of the loom and sustaining the feeder or hopper for the filling-carriers, the transerrer f', fulcrumed on the stud f, the controlling rock-shaft d' to govern the time of operation of the replenishing mechanism, and the lay A⁸, having a bunter C² thereon to effect the operation of the replenishing mechanism at the proper time, may be and are all substantially as in United States Patent No. 529,940 and operate substantially as therein set forth.

The replenishing shuttle-box on the end of the lay adjacent the replenishing mechanism is shown in Fig. 2 and comprises a front box, plate, or wall b, top plate b', and back plate b'', and a binder B is fulcrumed at its outer end on the lay at b^X and acted upon by a light spring B^X and also co-operating with an upturned binder-finger P' on the usual protector-shaft P, governed by the spring P^X.

When the shuttle S enters the box properly,

it is subjected to the pressure of the checking-springs B^x and P^x , transmitted through the binder, as will be manifest to those skilled in the art, and heretofore this entire pressure of the checking means has been maintained during filling-replenishment. At such time the transerrer f' conveys a filling-carrier from the filling feeder or hopper to the shuttle, and, as has been previously pointed out, the transerrer is at times faulty, owing to the firmness with which the shuttle is held from movement in the shuttle-box.

I have provided means herein to relieve the shuttle of binding pressure at the time of filling-replenishment, so that the shuttle can move slightly longitudinally or laterally, or both, to adapt itself properly to receive the incoming filling-carrier. To this end I have fulcrumed a lever h h' on the inner end of the stud f , the arm h of the lever projecting rearwardly and terminating in a tubular portion h^2 , and a longitudinal slot h^3 is provided between such tubular portion and the fulcrum. A bunter, shown as a plunger k having a shoulder k' , is slidably mounted in the tubular part of the lever, the front end of the plunger entering the slot h^3 and having secured to it a stop-collar k^x . A coiled spring s^x surrounds the plunger between the front end of the tubular part h^2 and the shoulder k' of the plunger to normally retain the latter in extended position, (shown in the drawings,) the front end of the part h^2 being reduced to form a shoulder h^{20} , Fig. 3, against which bears the front end of the spring. The spring s^x permits the plunger to be pushed into the part h^2 slowly when the device is in operation, and so acts as a cushion to prevent undue shock. The front arm h' of the lever is provided with a lateral pin h^4 , which enters a cam-slot d^{10} in an upturned arm made fast to the rock-shaft d' by a suitable set-screw 6, Fig. 1, and preferably said arm is made longitudinally adjustable, the two parts d^{11} and d^{12} being adjustably connected by bolts 8.

Ordinarily the parts just described are in full-line position, Fig. 1, and when the lay beats up the rear end of the bunter or plunger k passes over the top of the replenishing shuttle-box near its mouth. When the replenishing mechanism is to operate, however, the controlling rock-shaft d' is turned in the direction of arrow 65, Fig. 1, throwing the arm d^{11} d^{12} forward into dotted-line position, and the slot-and-pin connection between the arm and the lever h h' turns the latter on its fulcrum f into dotted-line operative position. Such depression of the rear end of the plunger k moves it into the path of movement of an offset extension p^x on the binder-finger P' in the present embodiment of my invention, and as the lay beats up the plunger will engage such extension, and the plunger will compress its spring s^x until the latter is strong enough to overcome the force of the protector-spring P^x and swing the binder-finger back away from the binder just before the filling-

carrier engages the shuttle. Thus the latter is relieved of the pressure due to the protector-spring P^x and subjected only to the action of the light spring B^x , which latter will not interfere with the adaptation of the shuttle to the incoming filling-carrier. The shuttle is not again subjected to the regular binder-pressure until the transfer of filling has been effected and the lay has moved back far enough to release the binder-finger from the control of the bunter or plunger k .

Manifestly the bunter could be made rigid, if desired; but by yieldingly mounting or cushioning the same I prevent undue shock or jar when it operates. By adjusting the arm d^{11} d^{12} the rear end of the bunter can be made higher or lower when it is in operative position, according to the height of the shuttle-box or adjacent parts.

My invention is not restricted to the precise construction and arrangement shown and described in the practical embodiment thereof comprised herein, as the same may be modified or rearranged in various details by those skilled in the art without departing from the spirit and scope of my invention.

Having fully described my invention, what I claim as new, and desire to secure by Letters Patent, is—

1. In a loom provided with automatic filling-replenishing mechanism, the lay, shuttle-checking mechanism mounted thereon, and means mounted independently of the lay and operative upon filling-replenishment to yieldingly act upon said shuttle-checking mechanism and reduce the pressure upon the shuttle due to such checking mechanism.

2. In a loom, a lay having a shuttle-box, a spring-controlled binder therefor, mechanism to replenish automatically the shuttle with filling, and means mounted independently of the lay to engage the binder and reduce the binder-pressure on the shuttle at the time of filling-replenishment.

3. In a loom, a lay having a shuttle-box, a spring-controlled binder therefor, mechanism to replenish automatically the shuttle with filling, and means mounted independently of the lay and rendered operative by or through actuation of the replenishing mechanism to engage the binder and reduce the binder-pressure on the shuttle.

4. In a loom, a lay having a shuttle-box, a protector mechanism, including a binder for the shuttle, mechanism to replenish automatically the shuttle with filling, and means mounted independently of the lay and operative at time of filling-replenishment to relieve the shuttle from pressure due to the protector mechanism.

5. In a loom, a lay having a shuttle-box, a binder, a co-operating spring-controlled binder-finger, automatic filling-replenishing mechanism, and means mounted independently of the lay to yieldingly engage and retract the binder-finger from the binder at the time of filling-replenishment.

6. In a loom provided with automatic filling-replenishing mechanism, a rock-shaft to control the time of its operation, shuttle-checking mechanism, and means directly connected with and governed by said controlling rock-shaft at the time of filling replenishment to coöperate with the checking mechanism and reduce the pressure upon the shuttle.
- 10 7. In a loom, a lay having a shuttle-box, a binder, a coöperating spring - controlled binder-finger, automatic filling - replenishing mechanism, and a yieldingly-governed bunter mounted independently of the lay to coöperate with and retract the binder-finger from the binder at the time of filling replenishment.
- 15 8. In a loom, a lay having a shuttle-box, means to yieldingly engage and check the shuttle when it enters the shuttle-box, mechanism to replenish automatically the shuttle with filling when the shuttle is properly boxed, and means mounted independently of the lay and operative automatically at the 20 time of filling replenishment to permit relatively free movement of the shuttle to adapt itself for the proper reception of the fresh filling.
- 25 9. In a loom, a lay having a shuttle-box, a binder, a coöperating spring - controlled binder-finger, automatic filling-replenishing mechanism, a normally inoperative, spring-controlled bunter mounted independently of the lay, and a connection between said bunter and the replenishing mechanism to move the 30 bunter into position to engage and retract the binder-finger from the binder during filling replenishment.
- 10 10. In a loom, a lay provided with a shuttle-box, a shuttle to contain a supply of filling, 35 shuttle - checking mechanism, filling-replenishing mechanism, including a transerrer, to provide the shuttle automatically with a fresh supply of filling, and means mounted independently of the lay to reduce the pressure 40 of the checking mechanism upon the binder as the transerrer conveys a supply of filling to the shuttle.
- In testimony whereof I have signed my name to this specification in the presence of 45 two subscribing witnesses.
